UNITED STATES PATENT OFFICE.

CLIFFORD C. COULTER, OF PORTLAND, OREGON.

GAS-STOVE.

1,123,175.

Specification of Letters Patent.

Patented Dec. 29, 1914.

Application filed January 24, 1914. Serial No. 814,854.

To all whom it may concern:

Be it known that I, CLIFFORD C. COULTER, a citizen of the United States, and a resident of the city of Portland, county of

5 Multnomah, State of Oregon, have invented a certain new and useful Improvement in Gas-Stoves, of which the following is a specification.

My invention has for its object to provide 10 a gas stove which shall prevent the fumes of combustion escaping into the room, but carrying them, instead, to the exterior of the building. The same construction also provides protection against the room becoming filled with gas, in case of the accidental extinguishing of the flame, after the burner has been turned on and lighted.

My invention further has for its object to draw in and heat the cold air from the floor 20 of the room; also to cause the air so drawn in to be highly heated in its passage through my stove.

My invention further has for its object to attain all the above described results in 25 an inexpensive, durable stove.

The details of construction and operation of my stove are hereinafter fully described.

In the accompanying drawings: Figure 1 is a front elevation of my stove; Fig. 2 is 30 a vertical section taken on the line 2—2 of Fig. 1; Fig. 3 is a top view of the stove with portions of the upper plate broken away, the arrows indicating the direction of the air currents while being heated; Fig. 4 is an 35 enlarged fragmental vertical section on the line 4—4 of Fig. 3; Fig. 5 is a horizontal section on the line 5—5 of Fig. 4; and Fig. 6 is a detail of the safety check valve.

a is the casing of my device, resting on 40 legs b. The front of the casing is provided with a door c. Angle irons, d, on the inside form a supporting medium for the bottom plate, e, of the chamber provided in the top of my stove for efficiently heating the air 45 drawn in and through my stove from the floor of the room. The plate, e, is made with parallel ribs f (as shown in Figs. 2 and 3) constituting baffle plates or partitions compelling the air circulated through 50 the stove to pass over highly heated surfaces, and so become highly heated. Also integral with the plate, e, and located beneath it, is a housing g. A cover h, provided with holes, i, is adapted to form a 55 closure for the top of my stove. The plate, e, is provided at its diagonal corners with

holes j, and pipes k, flaring at their lower ends, connect the upper side of the plate, e, with the air under the bottom of the stove. A pipe m (see Fig. 2) connects the interior 60 of the housing, a, with a chimney flue (not shown), and is adapted to carry off all gases generated by the burning of the gas. A pipe n connects the interior of the inner 65 housing g with the air exterior of the casing a, and is in parallel alinement with the pipes k. Both ends of said pipe n are flared. The pipe n comprises two sections connected by a nipple n'. See Figs. 2 and 6. The top of said nipple n' is provided 70 with a screen n², and a flop-valve n³ is adapted to close the upper end of the nipple n'. Said valve n³ is made of very light 75 material, so that it will open under the influence of a light upward draft, but will be closed when the direction of draft is reversed. The screen n² is to reinforce the valve against bursting under a heavy downward pressure. A gas-inlet pipe, o, provided with an air mixer r and a valve, s, 80 extends inwardly through the casing, a, and into the pipe n, and is carried upward through the latter into the inner housing g, where it connects with a gas burner t. The inner housing g is provided with a door u, 85 located in alinement with the door c, and holes v in the bottom of the inner housing open out into the interior of the casing a. A water heating coil, w, is located over the burner t, the inlet of this pipe being indicated at w' and the outlet at w².

The action of my device is as follows: When the valve, s, is opened the burner may be lighted through the doors, c, u, and after the air mixer r has been adjusted so as to 95 give the proper intermixture of gas and air the doors, c, u, are closed. The heat from the flame will raise the temperature of the plate e, and the air will rise through the orifices, i, in the top h, thus creating an air 100 current in the direction indicated by the arrows in Fig. 3. The air-inlet pipes k being connected with the coldest stratum of air in the room, will continually draw cold air up through the orifices j. In this way 105 the coldest air of the room will always be heated, instead of reheating the warm air, as is commonly done in the types of gas stoves now used. The pipe, n, opening directly beneath the burner t, will act as a 110 blast against the flame, so as to carry it up directly against the plate e. The gaseous

products of combustion being heavier than air will locate in the lower part of the inner housing *g* and thence will escape through the holes *v* into the casing *a*, from which they will be carried by the pipe *m* to the atmosphere. Escape through the pipe *n* will be prevented by the check valve *n³*.

Since there is no outlet for the gases in the inner housing *g* except through one of the bottom orifices *v*, and since the gaseous products of combustion are heavier than air, the air of the room heated by my stove will always remain uncontaminated. My stove also protects against the room becoming filled with gas by the accidental extinguishing of the flame while the gas is turned on. The baffle partitions *f* in the air heating chamber at the top of my gas stove insure an efficient heating of the air circulated through my gas stove by compelling the air current to follow a circuitous passage in escaping from the top air heating chamber.

The outer casing of my stove, by inclosing the inner housing, holds the hot air emitted from the latter in the form of an efficient insulating medium, which serves as a heat retainer for the inner housing. The result is economical and efficient use of the heat generated by my stove before the heated products of combustion are carried to the exterior through the pipe.

I claim:

1. The combination with a room, of a gas stove comprising an outer casing inclosed on all sides, top and bottom, an air heating chamber located within the top of such casing, inlet air tubes extending into such heat-

ing chamber through said outer casing, a combustion chamber located centrally within the outer casing and directly under said heating chamber, said combustion chamber having an opening at the base into the outer casing, a gas burner in such combustion chamber, a pipe connecting said burner with a gas supply, an air inlet pipe leading from exterior the outer casing into the combustion chamber, a check valve in such air inlet pipe adapted to close against an outflow, and an outlet pipe connecting the lower part of the outer casing with the atmosphere exterior of the room.

2. A gas stove comprising an outer casing inclosed on all sides, top and bottom, an air heating chamber located within the top of such casing, inlet air tubes extending into such heating chamber through said outer casing, a combustion chamber located within the outer casing and directly under said heating chamber, said combustion chamber having an opening at the base into the outer casing, a gas burner in such combustion chamber, a pipe connecting said burner with the gas supply, an air inlet pipe leading from exterior the outer casing into the combustion chamber, a check valve in such air inlet pipe adapted to close against an outflow, and an outlet pipe connecting the lower part of the outer casing with the atmosphere.

CLIFFORD C. COULTER.
